CLAIM

The ornamental design for a document printer, as shown and described.

DESCRIPTION

FIG. 1 is a front perspective view of a document printer showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a front perspective view showing the door in open position.

The broken lines in FIG. 7 are for purposes of illustration only and form no part of the claimed design.

FIG. 1

FIG. 2

FIG. 3

FIG. 4
